CLAIM

The ornamental design for a case for coordinated rapid movement testing, as shown.

DESCRIPTION

FIG. 1 is a top perspective view of a case for coordinated rapid movement testing showing our new design; FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof; and

FIG. 8 is a view in cross section taken along line 8—8 of FIG. 2.

FIG. 1
